UNITED STATES PATENT OFFICE.

ISAAC SCOTT WALTER, OF DELAWARE, OHIO.

HAMMER.

Application filed January 5, 1924. Serial No. 684,628.

To all whom it may concern:

Be it known that I, ISAAC SCOTT WALTER, a citizen of the United States, residing at Delaware, in the county of Delaware and 5 State of Ohio, have invented a new and useful Hammer, of which the following is a specification.

This invention relates to a hammer designed primarily for use by glaziers, one 10 of the objects being to provide a hammer the head of which is so shaped that it can be used for driving in any one of several different directions without changing the position of the user at one side of the glass 15 light.

A further object is to provide a hammer of this character the head of which can slide easily over the surface of a glass light and will strike squarely against points close 20 to the surface of the light.

Another object is to provide the hammer with a concave surface so that it can be slid over any irregularities of the surface or the like without danger of missing the 25 glazier's point.

With the foregoing and other objects in view which will appear as the description proceeds, the invention resides in the combination and arrangement of parts and in 30 the details of construction hereinafter described and claimed, it being understood that changes in the precise embodiment of the invention herein disclosed may be made within the scope of what is claimed without departing from the spirit of the invention.

In the accompanying drawings the preferred form of the invention has been shown.

In said drawings

40 Figure 1 is a top plan view of the hammer. Fig. 2 is a side elevation thereof, the head being shown in section.

Fig. 3 is a bottom plan view of the hammer.

45 Referring to the figures by characters of reference 1 designates the head of the hammer provided with three flat extensions 2, 3 and 4 disposed at right angles to each other and having flat faced terminal ends 50 or butts 5 constituting striking faces. Out-

standing from one face of the head between the extensions 2, 3 and 4, is an extension 6 substantially in the form of a truncated pyramid and providing a striking face 7. A handle 8 is extended from the head at 55 that side thereof opposite the extension 3 and is preferably inclined relative to the faces of the head, the free end of the handle terminating in a grip 9. Thus while the head is held flat against the surface of a 60 glass light L as shown in Fig. 2 sufficient space will be provided between the grip 9 and the light to enable the handle to be grasped firmly by the user.

To enable the head to slide smoothly over 65 an uneven surface, the bottom face of the head is recessed as shown at 10.

It will be apparent that after the head has been placed flat against the surface of the glass light, it can be swung against 70 glaziers' points that have been properly positioned at all sides of the light, thus driving the points without the necessity of shifting the position of the operator.

The extension 6 provides weight for the 75 head and can also under some conditions be used for hammering tacks, etc.

What is claimed is:—

A glazier's hammer including a head, having a recess in one face, an angular extension 80 upon the opposite face of the head providing a weight and constituting a striking portion, the flat face of which is opposite the center of the recess, a handle extending from one side of the head, and flat relatively 85 thin angular extensions projecting from the other sides of the head, all of said extensions having flat faces occupying the same plane with the recessed face of the head, said flat extensions constituting means 90 for driving points in either of three directions while the head is in sliding engagement with a supporting surface.

In testimony that I claim the foregoing 95 as my own, I have hereto affixed my signature in the presence of two witnesses.

ISAAC SCOTT WALTER.
